Inventor:
A. Peshout

UNITED STATES PATENT OFFICE

ANTON PESHOUT, OF SAN FRANCISCO, CALIFORNIA

CHRISTMAS TREE STAND

Application filed August 17, 1931. Serial No. 557,648.

This invention relates to stands for Christmas trees and similar articles.

Objects of this invention are to provide a device which may be readily assembled by an unskilled operator, which may be readily separated into its component parts and stored in a small space, and which may be shipped in a knock-down condition, either with the parts grouped in separate units, or with the parts shipped in bulk.

Further objects are to provide a Christmas tree holder having a small number of parts, and which may be made from few patterns at an extremely small expense.

An embodiment of the invention is shown in the accompanying drawing, in which:—

Figure 1 is a plan view of the Christmas tree stand, as a whole, in its assembled condition.

Figure 2 is a cross-section view of the body and holder part of the Christmas tree stand in its assembled condition, and showing the legs or supports fitted inside of the body part of the holder.

Figure 3 is a half cross section view of the body and holder part of the invention in its assembled condition, without the legs or supports, when looking straight down from the top on the invention.

Referring more particularly to the drawing, it will be seen that the device comprises a substantially cylindrical shaped body 4 to receive, and within which are assembled the various other parts of the invention. This cylindrical shaped body 4, at its lower end receives and holds in place the three or more legs or supports, numbered 1 on the drawing. No machine work is required on any part to fit the legs or supports 1, to the body part 4, of the invention. The lower part of the body 4, is provided with an aperture, numbered 2, adapted to receive a threaded screw, numbered 8, which holds the legs or supports, numbered 1, in a rigid position.

The lower portion of the body, numbered 4, is also provided with an aperture, numbered 3, adapted to receive a two-way—right and left thread—threaded adjusting screw, numbered 7. This screw holds in position and regulates the two adjusting clamps, numbered 5

and 6. By turning this screw, numbeded 7, to the right, by means of a winged nut, numbered 9, the two adjusting clamps are drawn toward each other and hold fast and rigid the butt end of the tree, and when turned to the left, by means of the winged nut 9, the butt end of the tree is loosened and released. Two guiding breeches, numbered 10, are provided as a part of the body 4, which hold the adjusting clamps, 5 and 6, in position when 60 being operated and adjusted.

The two adjusting parts, numbered 5 and 6, are provided for holding the butt end of the tree fast and rigid and in an upright position. These two parts, 5 and 6, are held in position and regulated by means of the two-way—right and left thread—threaded adjusting screw 7, which is held by an aperture, numbered 8, in the lower end of the cylindrical shaped body 4. The two adjusting parts 5 and 6, have a threaded aperture, numbered 11, in the lower end of each to receive the two-way adjusting screw 7. These adjusting parts 5 and 6 may be regulated to hold any size tree by means of a winged nut, numbered 9, attached to one end of the two-way threaded adjusting screw 7, by one simple operation.

A plurality of legs or supports, numbered 1, are provided and have slightly enlarged rounded bearing outer portions, numbered 12, adapted to rest on the floor. The upper parts of these legs or supports are provided with a circular part, numbered 13, which is shaped to fit inside of and be held by the cylindrical shaped body, part 4. These legs or supports are held in position by the very simple means of a set screw, numbered 8, which fits into a threaded aperture, numbered 2, at the lower end of the cylindrical shaped body. This set screw 8, tightens and holds securely the legs or supports, numbered 1, by means of a winged turning device, which is a part of the set screw. In this manner the legs or supports are firmly locked in position and may not inadvertently be dropped from the cylindrical shaped body part 4 when the whole device is lifted from the floor.

Attention is particularly called to the fact that extremely simple patterns may be used

in producing the parts and that a very small number of patterns may be employed. In the form shown only three simple patterns may be employed, one for the cylindrical shaped body part 4, one for the circular shaped clamping device parts numbered 5 and 6,—as the two are duplicates, and one for the leg or support, part 1, as the legs or supports are all duplicates.

10 By the construction outlined, it is possible to make these tree stands very cheaply, to ship them in a collapsed condition, to readily assemble the parts, or separate the device into its component parts, such operations being easily performed by an unskilled operator.

It should also be noted that very little machine work is required in manufacturing the parts, the only machine work required being that of drilling and threading one hole in the cylindrical shaped body part 4, to make the aperture numbered 2, to receive the set screw 8, which holds in position the legs or supports numbered 1, and drilling and threading an aperture, numbered 11, in the clamping parts 5 and 6, to receive the two-way threaded screw part 7. The two-way threaded screw part 7, has a winged turning device, numbered 9, attached to one end only 25 for turning the screw to adjust the two adjusting clamps, 5 and 6.

It is of course understood that the exact number of parts described may be varied and other changes in the embodiment of the invention may be resorted to without departing from the spirit of the invention, such invention being limited only as set forth in the appended claims.

I claim:—

40 1. A tree holder comprising a cylindrical shaped body or cup adapted to receive the butt of a tree, a set of two clamps set inside of such cup and adapted to hold a tree rigid by means of a two-way threaded adjusting screw, a plurality of legs or supports extending outwardly and downwardly from the inner portion of said cup and having an upper circular portion fitted inside of said cup and held in position by means of a single set screw 45 at the lower portion of said cup.

50 2. A tree holder comprising a cylindrical shaped body or cup, two semi-circular tree engaging clamps set inside of said cup and held in adjusted position by a two-way threaded adjusting screw in said cup, a plurality of legs or supports extending outwardly and downwardly from the inner portion of said cup and held in position by means of a set screw at the lower portion of said 55 cup.

60 3. The combination of a set of two clamps to receive the butt of a tree, adjustable by means of a two-way threaded screw and held in position by a cylindrical shaped body or 65 cup, a plurality of legs extending outwardly

and downwardly from the inner portion of said cup and held in position by means of a set screw set into the lower portion of said cup.

4. The combination of a plurality of legs 70 extending outwardly and downwardly from the inner portion of a cylindrical shaped body or cup and held in position by means of a winged set screw, a set of two clamps adaptable for holding the butt of a tree by 75 means of a two-way threaded winged screw held in place by said cylindrical cup shaped body part, and guide members for said clamps located within said cup member.

In witness whereof, I have signed my 80 name to this specification.

ANTON PESHOUT.
